UNITED STATES PATENT OFFICE.

CHRIST SKOLNEEK, OF CLEVELAND, OHIO.

LOCK.

1,356,747.

Specification of Letters Patent. Patented Oct. 26, 1920.

Application filed November 6, 1919. Serial No. 335,998.

To all whom it may concern:

Be it known that I, CHRIST SKOLNEEK, a subject of the Government of Courland, in the Baltic Province, residing at Cleveland, 5 in the county of Cuyahoga and State of Ohio, have invented certain new and useful Improvements in Locks, of which the following is a specification.

This invention relates to a lock for doors 10 and particularly to that type of lock which is commonly mortised within the frame work of the door, but which may with slight modifications be applied to the exterior thereof.

15 The lock consists of that type in which a plurality of tumblers are pivotally secured and which must be brought into a predetermined position by the turning of the key before the bolt may be moved.

20 Further and more limited objects of the invention consists of means employed for operating the tumblers and bolt, the arrangement of the parts being such as to obviate the necessity of numerous moving 25 parts such as springs, levers and gears, which are more or less commonly used in this type of lock.

To enable others skilled in the art to make and use this improvement, the lock and its 30 construction and operation will now be described.

Referring to the drawings wherein like reference numerals designate similar parts of reference throughout the various views, 35 Figure 1 is an elevation of a lock with the cover plate removed; Fig. 2 is a horizontal section on the line 2—2 of Fig. 1 and looking in a direction of the arrows; Figs. 3 and 4 are sectional details taken on the corresponding lines 3—3 and 4—4 of Figs. 1 and 2, and Fig. 5 is a sectional detail of a special key used for operating the lock.

The lock consists of a rectangular casing 1 which is closed by a cover 2 being held in 45 place at the corners by screws 3, said screws being threaded within the enlarged corners 4 of the casing 1. Slidably mounted upon a stud bolt 5 threaded upon one side of the casing 11 is a bolt 6. This bolt is provided 50 with an enlarged end 7 which projects through an opening in the side of the casing and enters a corresponding aperture in the frame work of the door casing. At the opposite end the bolt is provided with a slot 8 through which extends the stud bolt 5, and in this manner the bolt is supported at both

ends and is allowed freedom to reciprocate longitudinally of the casing. At the bottom of the bolt and substantially at its middle is provided an arcuate opening 9 which is 60 engaged by the key whereby to operate the bolt as will be more fully described.

Pivots supported upon stud 5 and equally distributed upon each side of the bolt 6 are a plurality of tumblers 10, said 65 tumblers are provided with a longitudinal slot 11, the ends of which open upwardly and laterally therefrom into notches 12 which are slightly curved concentric with the pivot point of the tumblers. These 70 notches 12 are engaged by a pin 13 carried by the bolt and act to prevent the bolt from being manipulated. The tumblers 10 are normally held in a locked position with respect to the bolt 6 by means of a leaf spring 75 14 which has one of its ends bearing upon the upper face of the tumblers and the opposite end secured to the bracket 15 formed as part of the casing 1. The lower faces of the tumblers are each provided with openings 16 which are concentric with the pivot point 17 of the key and which are engaged by the various portions of the key in a proper manner to elevate the tumblers as will be 80 more fully described hereinafter.

85 The pivot point 17 for the key comprises a pin which is rigidly secured to the side of the casing 1. The key hereinbefore referred to consists of a hollow shank 18 having a handle 19 made integral with one end thereof and a bit 20 at the opposite end. The bit 20 is provided with a plurality of faces or steps 21 which being on a different plane thereby to act in conjunction with the recesses 16 of the tumblers. Within the shaft 90 18 is rotatably mounted a second shaft 22, this shaft is provided at that end which projects into the handle 19 with a knurled operating wheel 23, and at its opposite end with a bit 24 which is constructed with various steps as described for the bit 20. With 95 the parts constructed as above described the operation of the lock is as follows:

The shaft or stem 22 of the key is rotated with the hollow shaft 18 by the wheel 23 100 until the bits 20 and 24 are in perfect alignment. The shank of the key is then inserted through the opening 25 provided in the cover plate 2 until the pivot point 17 occupies the bore 26 of the key. The first action 110 then is to rotate the shaft 22 until the bit 24 has engaged the tumblers 10 on one side

- of the bolt in such a manner as to cause them to swing upon their pivots sufficiently to allow the pin 13 to clear the passage 12 and to occupy the passage 11, the other portion 5 of the key being then rotated by means of the handle 19 until the bit 20 and its faces 21 have similarly engaged and acted upon the tumblers on the opposite side of the bolt whereupon continued rotation of the key 10 will cause the enlarged face 27 of the bit 20 to engage the arcuate opening 9 of the bolt and enable the bolt to be moved forwardly. When the bolt has reached the position 15 shown in dotted lines in Fig. 1 the pin 13 is in a position to allow the spring to force the tumbler downwardly so that the pin may engage the passage 12. This then holds the bolt in a locked position until the operation is reversed.
- 20 By the foregoing it will be seen that a lock is provided which is simple and efficient in operation, cheap of manufacture and durable, and while I have shown and de-

scribed this specific means I do not wish to limit myself in the construction of the 25 same further than is required by the state of the art or that which comes within the scope of the appended claim.

I claim:

In a lock, the combination of a casing, 30 a pin in said casing, a reciprocating bolt in the casing, having a longitudinal slot through which said pin extends and forms a guide for the inner end of said bolt, a plurality of tumblers pivoted on said pin, at opposite sides of the bolt, said tumblers having slots offset at their ends, and a pin carried by the bolt and adapted to engage in the offset parts of the slots in the tumblers.

In testimony whereof, I do affix my signature in presence of two witnesses.

CHRIST SKOLNEEK.

Witnesses:

JOHN A. BOMMHARDT,
G. V. ROSENBERG.
